UNITED STATES PATENT OFFICE

154,528

DESIGN FOR A SHOE

Louis E. Beaudin, Hanover, Pa., assignor to L. E. Beaudin Shoe Company, Hanover, Pa., a corporation of Pennsylvania

Application November 18, 1948, Serial No. 149,699

Term of patent 3½ years

(Cl. D7—7)

To all whom it may concern:

Be it known that I, Louis E. Beaudin, a citizen of the United States, and a resident of Hanover, county of York, State of Pennsylvania, have invented a new, original, and ornamental Design for a Shoe, of which the following is a specification, reference being had to the accompanying drawings forming a part thereof, wherein:

I claim:

The ornamental design for a shoe, substantially as shown.

LOUIS E. BEAUDIN.
